UNITED STATES PATENT OFFICE.

FRANK A. HUMPHREY, OF WORCESTER, MASSACHUSETTS, ASSIGNOR, BY MESNE ASSIGNMENTS, TO KATE AUGUSTA HUMPHREY, OF SAME PLACE.

GUIDE FOR SAW-MACHINE TABLES.

SPECIFICATION forming part of Letters Patent No. 623,156, dated April 18, 1899.

Application filed October 6, 1897. Serial No. 654,222. (No model.)

To all whom it may concern:

Be it known that I, FRANK A. HUMPHREY, a citizen of the United States, residing at Worcester, in the county of Worcester and State of Massachusetts, have invented a new and useful Improvement in Guides for Saw-Machine Tables, of which the following, together with the accompanying drawings, is a specification sufficiently full, clear, and exact to enable persons skilled in the art to which this invention appertains to make and use the same.

One part of my invention relates to the manner of supporting the work gage or guide in connection with a circular-saw table or similar machine-table, whereby the guide is maintained in proper position by a peculiarly-constructed guide-head and grip devices under-locking and engaging a downward flange extending along the edge of the table, the objects being to afford a perfectly plain top surface on the table, obviate liability of the guide mechanism becoming clogged with chips or sawdust, and to provide an efficient, serviceable, and conveniently-adjustable guide mechanism of the nature described.

Another part of my invention relates to the employment, with a saw-guide having a head supported in connection with a depending flange at the edge of the table, of a hand-shaft and gearing for traversing the guide along the edge of the table and a holding device therefor, the object being to afford a means whereby the guide can be easily moved across the table-surface, accurately adjusted, and readily secured at any desired position, as more fully hereinafter explained.

Another feature of my invention consists in providing for circular-saw tables having a flanged edge a sawing-guide comprising an arm and a supporting-head confined to and movable along the edge of the table and having means for the lateral regulation of the alinement of the guide-arm relatively to its supporting-head and to the plane of the saw.

Another part of my invention relates to means for securing the rear end of the guide-bar to the rear edge of the saw-table, the object being to provide a saw-guide with efficient devices for rigidly clamping the end of the guide to the edge of the table and with

appliances under convenient control of the operator from his position in front of the machine for unlocking and locking said clamping devices to facilitate shifting and adjusting said guide, as more fully hereinafter explained.

Another part of my invention relates to the construction and arrangement, in connection with the sawing-guide and its supporting-head, of an extension-bar and gage-stop, as hereinafter explained, the object being to afford an efficient and serviceable gage for long cut-off work; also, to provide a gage-stop that is adapted for ready adjustment to different positions and for sustaining the outer end of long work to prevent the same from sagging below the gage.

These objects I attain by mechanism the nature and construction of which are explained in the following description, the particular subject-matter claimed being hereinafter definitely specified.

In the drawings, Figure 1 is a plan view of a saw-table top having gages or guides thereon, illustrating the nature of my invention and showing the arrangement of the guide as employed for a front or slitting guide, also the arrangement of the guide as adapted for a side or cut-off guide with an extension-bar and adjustable gage-stop for use with long work. Fig. 2 is a section of the extension-bar and front view of the gage-stop. Fig. 3 shows the side views of the gage-stop in its two positions of adjustment. Fig. 4 is a cross-section of the guide, showing the manner in which the reversible high fence is combined therewith. Fig. 5 is a vertical sectional view through the head of the guide and front edge of the saw-table, also the connecting end of the attachable extension-bar. Fig. 6 is a front view of the guide-head. Fig. 7 is a bottom view of the guide and a portion of the saw-table with its rack and guide-supporting flange, the bottom part of the guide-head being in section to reveal the inclosed mechanism. Fig. 8 is a transverse vertical section through the guide-head and saw-table top, looking toward the front end of the same. Fig. 8^a is a vertical section showing the adaptation of my invention to a wooden saw-table. Fig. 9 is a longitudinal section at line

x x, Fig. 10, showing the mechanism for clamping the rear end of the guide to the rear edge of the saw-table. Fig. 10 is a bottom view of the rear-end-clamping devices. Fig. 5 11 is a rear end view of the same, and Fig. 12 is a vertical section at line *w w* on Fig. 9.

Referring to parts, A denotes my improved saw gage or guide, which comprises a guiding beam, arm, or tongue *a'* and a guide-head *a*', whereby said tongue is carried and supported in connection with the edge of the machine-table, and B indicates the detachable extension-bar, sometimes employed for increasing the working length of the guide.

15 C indicates the saw-table, C' its throat-block, and *c*² the throat slot or opening through which the circular saw G projects. The table is formed with a plain and smooth top surface unbroken by grooves or openings such as are

20 usually required for attaching guides thereto. The edges of the table are squared with the plane or axis of the saw, and a downwardly-projecting flange C³ is provided along each edge of the table, said flange being slightly beveled or made thinner at its lower edge, as indicated in Fig. 5. The flanges C³ terminate some distance short of the corners of the table, leaving unflanged portions or spaces C⁵ of sufficient dimension to accommodate the

25 passing of the guide-head *a*' laterally on and off the edge of the table at either corner. The head of the guide is best made about fifteen inches long, more or less, its central portion forming a slot for the tongue *a'* level

30 with the top surface of the table, while the top of its lateral wings is at somewhat lower level, so as not to interfere with any work laid upon the table and projecting over the edge. The tongue *a'* is best formed in cross-section as two parallel upright flanges 4, connected by a web or lattice. The fore end of said tongue is seated upon the outwardly-projecting part of the head and connected therewith by a pivot-stud 5. An angle-piece 6 is rigidly bolted to the tongue, and its lip extends downward within or through an opening 7 in the head. A pair of opposite laterally-disposed screws 8, threaded in the sides of the head, with their points engaging de-

35 pressions formed in the sides of the downward lip on the angle-piece, serve for regulating the alinement or lateral adjustment of the tongue *a'* relatively to the head and to the plane of the saw by slightly swinging the tongue on its pivot-stud 5, one screw being turned outward and the other inward, as may be required. The tongue is preferably provided with vertical holes 9, formed through suitable bosses integral with the web and

40 flanges and disposed at proper distance apart and on the exact center line between the guide-faces. These holes serve for the support of a detachable high fence 10, (see Fig. 4,) which can be reversed and used at either side of the guide, as hereinafter explained.

The under part of the head *a*' extends beneath the table-flange and has an upward rib

or flange 11 at the inner side thereof, the head thus forming a long pocket or cradle 12, within which is arranged a friction bar or 70 plate 13, made of wood or suitable material and beveled to match the inner surface of the table-flange C³. Said bar rests loose within the pocket, but is confined from endwise and downward escape by the ends and bottom 75 part of the head. A bow-shaped spring 14, of flat steel, is arranged, as shown, at the back of the friction-bar, with its end bearing against said bar and pressing it toward the flange. Set-screws 15, having check-nuts thereon, are 80 threaded into the inner rib 11 of the head and adapted to be turned in against the ends of the spring 14 for giving a dead-stop to the spring when it is forced back to the given position maintained by the point of the screw. 85 The adjustment of the spring and screws 15 is such as will give just a free sliding action of the friction-bar upon the flange while affording sufficient rigidity against any angular action of the head, due to side pressure 90 against the tongue.

The wood bar 13 is best saturated or filled with paraffin or other lubricant, so as to slide against the table-flange without stickiness, and acts against said flange both as a guide 95 and as a tightener.

A toothed rack 16 is attached to the under side of the table near to and parallel with the flange C³, that extends along the front edge. A forwardly-projecting rotatable shaft 17 is mounted in the head below the tongue, carrying near its inner end a gear 18, that connects, through the aid of an intermediate gear or gears 19, with the rack 16, fixed to the table. The outer end of the shaft is provided with a hand wheel or grip 20, having a long hub that embraces the shaft and abuts against the bearing at its rear end. The portion of the shaft within the hub is of square section or otherwise formed to prevent independent rotation while permitting endwise play of such shaft within the hub. The outer end of the shaft is screw-threaded, and a thumb-nut 21 is arranged thereon that turns in against the end of the hand-wheel hub. The outer end of the hand-wheel is preferably hollowed out or cup-shaped for partially covering the nut 21, as best shown in Figs. 5 and 6. The gear 18 is fixed to the shaft 17, and a large washer or plate 23 is preferably arranged on the shaft between the side of the gear and the friction-bar 13. This washer is not essential to the operation, but improves the wearing qualities of the mechanism. It may in some instances be omitted.

When the thumb-nut 21 is tightened, the shaft and gear 18 are drawn forward by the endwise pull of the shaft through the hand-wheel hub, and the friction-bar is forced against the table-flange C³, firmly clamping 130 said flange between the face of the head that rests against the edge of the table and the friction-bar that rests against the inner face of the flange, and thereby rigidly holding the

guide at any adjusted position. When the nut is loosened, the friction-bar is released and the guide can be shifted along the flanged edge of the table. A headed stud 22 is arranged in the outer end of the shaft for preventing the escape of the nut 21 from the end of the shaft, while allowing it ample scope and movement to tighten and loosen the parts. In the present instance two intermediate gears 19 are shown; but it will be understood that only one of such gears may in some instances be employed, or, again, if desired, the gear 18 can be arranged to mesh directly with the rack and the intermediate gears be omitted. Such latter arrangement is, however, not as convenient as with the intermediate gears, as shown, since by employing the two gears 19 the guide can be run by the gearing to the extreme edge of the table, as one intermediate gear will operate after the other of said gears has passed off the end of the rack. The guide A can readily be pushed across the table by hand when the clamp-nut 21 is released, the gears then rolling free on the rack. The guide-tongue may for general work be made with its rear end terminating at a position indicated by line D, Fig. 1; but for some classes of work it is desirable to have the guide extend over the full width of the table-top and to be secured at the rear edge of the table. For such instances the mechanism is made with a long guide-tongue a' and provided with a clamping device, preferably such as illustrated in detail in Figs. 9 to 12, inclusive. In the end of the guide-tongue there is arranged a vertically-movable grip-piece F, having an under lip f, that engages beneath the table-flange C³. Said grip slides through an opening formed in the tongue a' and is supported by suitable guide-lugs at the sides thereof. The lateral web of the tongue is provided with an inclined surface i in front and rear of said opening. A longitudinal bar I is disposed within the tongue, said bar having a wedge-shaped rear end I' that passes through an opening f' in the grip-piece F and rests on said inclined surface i at its lower side, while its upper side supports the grip-piece F, which latter may rest directly upon said bar, or, as in the present instance, be provided with a screw h for regulating the adjustment of the grip-piece relatively to the thickness of the bar and table. The head or fore end of the bar I is arranged to work in conjunction with an eccentric or cam m, that turns on a pin J, disposed transversely through the flanges 4 of the tongue, as shown, and said cam is provided with a handle m' at position to be reached and operated from the front of the machine and by which the operator can conveniently manipulate the grip devices as desired. When the handle is laid down, as in full lines, Fig. 9, the cam m forces the bar I rearward, and its inclined end, acting against the inclined surface i, tends to draw the grip-piece F upward, causing the edge of the table

to be firmly clamped between the lip f and the under surface of the guide-tongue. If the handle m' is turned upward, as per dotted lines, Fig. 9, the cam m draws forward the bar I, sliding its wedge-shaped end down the inclined surface i, and thus releases the grip-piece from its hold upon the flange C³, so that the guide can be moved freely along the edge of the table to right or left. The grip-piece and means for its operation being arranged between the lateral face edges 4 of the tongue, while the supporting-head is disposed below the surface level of the table or base level of the guide-tongue, there is no liability of any of the parts interfering with the free passage of any work past the saw.

The rear-end clamp when released does not interfere with the adjustment of the guide by means of the hand-knob and gears, and its handle being at a position well forward on the tongue the operator can, without leaving his position in front of the table, readily lift the handle m', loosen the thumb-nut 21, turn the hand wheel or knob 20 for shifting the guide, and reset the said handle and thumb-nut instantly, thus effecting the readjustment of the guide without material loss of time in the operation and without special attention to the placement of the rear end of the tongue beyond the act of raising and dropping the clamp-handle.

If the guide is used at the side of the table, there being no rack at that position, the head will move freely upon the flange, while the gears pass along the under side of the table without contact. When designed for use solely as a crosscut guide or gage, the head may in some instances be made without the hand-wheel and gears and clamp devices, since it is not essential that the guide for crosscutting should be fixed at one position, as its work is to slide forward and backward upon the side flange, the head being guided and maintained in square relation by the friction-strip 13 and underlocking lip 11, as before described. While a guide-head of this nature without securing devices would not be available for slitting-guide purposes, such form of guide-head with the securing devices, hand-wheel, and gearing is practically available for use on a crosscut-guide, as well as for a slitting-guide.

The high fence 10 consists of a plate of the desired length, having upon it two backwardly-projecting ears 24, that correspond with the bosses on the guide-tongue. Said ears have fixed therein vertical pins or dowels 25, that fit into the holes 9 and support the fence in upright position along the face of the guide, as indicated in section, Fig. 4. This improved means for supporting and centering the fence in combination with a guide affords facility for the adjustment and use of the fence in reverse position on either side of the tongue or its ready transfer and application to either the slitting or the cut-off guide. It can be instantly detached or re-

placed by simply lifting it to withdraw or insert the pins 25 from or into the holes 9.

To render the guide available for long work, I provide the detachable extension-bar B and 5 gage-stop b of the peculiar character illustrated. One end of said bar is fitted to the top of the guide-beam proper and is provided with an attaching thumb-bolt 26, the nut 28 of which can be underlocked into a space 29 10 in the tongue for holding the parts firmly together when the screw is tightened. (See Figs. 1 and 5.) The width of the bar B preferably corresponds to the width of the tongue a' and gives a straight edge surface flush 15 therewith.

The gage-stop b consists of a detachable clasp or sliding piece open at its under side and formed to set astride the bar or guide-tongue, as indicated in Figs. 1, 2, and 3. Said 20 stop is provided with projecting end lugs 30, against which the end of the board is placed for gaging the length to be cut off by the saw. The stop is also provided with laterally-projecting ledges or shelf-surfaces 31, 25 upon which the corner of the board or work is rested and upheld while being fed forward to the saw by the advance of the guide. The stop is secured to the bar B by a suitable thumb-screw 32 or by other suitable means. 30 The stop b is so made that when used upon the bar or tongue over the table-surface it can be set at inclined position, as shown at the right on Fig. 3, and the surface 33 at the angular lower end used as a gage-point against 35 which to place the end of the board when sawing it to a given length.

The extension-bar can be readily connected and detached as required. The guide can be slipped from the front edge of the table and 40 passed onto the flange at the side of the table, or vice versa, as required for use for cutting off or slitting work, and when used as a slitting-guide can be easily and accurately 45 adjusted by rolling the hand wheel or grip right or left and then quickly secured by a turn of the thumb-nut 21.

Fig. 8^a shows the guide applied to a wooden machine-table. In this modification the flange C³ is attached to the under side of the table 50 edge by screws, and a block 35, equal in thickness to the table, is introduced between the guide-tongue and guide-head. In other respects the parts are constructed and combined as above described. This guide may 55 be provided with the hand-wheel and gears similar to Fig. 5, in which case the rack 16 would be screwed to the wood table for engaging the gears in the same manner as shown on other figures of the drawings.

60 I claim as my invention and desire to secure by Letters Patent—

1. In combination with the machine-table having the plain ungrooved top surface, and provided with a downward lip or flange along 65 its edge, the guide or work-gage comprising an arm or tongue extending freely along the table-surface, and a guide-head carrying said

tongue movably supported on the edge surface of the table and underlocking said flange, a yielding presser carried in said guide-head, 70 acting against that surface of said table-flange opposed to the guiding-face of the guide-head, and a clamping device adapted for tightening said presser against the table-flange without disturbing the contact and alinement of the 75 guide upon, or in relation to the table edge, substantially as set forth.

2. The combination, of the machine-table provided with the downward lip or flange along its edge, the guide or work-gage comprising the tongue extending unconnectedly along the table-surface, and the guide-head carrying said tongue movably supported on the edge of the table and underlocking said flange, a friction-bar loosely confined within 85 said guide-head adjacent to the inward face of said flange, and means for tightening said bar firmly against the flange, for the purpose set forth.

3. The combination with the saw and the 90 saw-table having the depending lip or flange along its edge, the saw-guide comprising the tongue extending over the table-surface, and a transversely-disposed supporting-head attached to said tongue and underlocking the 95 flanged edge of said table, the friction-bar loosely confined within said guide-head, the back spring pressing said friction-bar toward the inclined face of said table-flange with yielding force, and check-screws limiting the 100 yielding action thereof, for the purpose set forth.

4. In combination with the machine-table having the downward flange along its edge, and provided with a toothed rack adjacent to 105 said flange, the guide or work-gage comprising the projecting tongue and the guide-head, said head supported at the edge of the table and underlocking the table-flange, the friction-bar within said guide-head at the rear of 110 the flange, the hand-wheel and shaft mounted in the guide-head, the hand-nut on the threaded fore end of said shaft, and the gearing connecting said shaft and rack, said shaft and its gear adapted for forcing the friction- 115 bar forward and clamping the guide-head on the table-flange when said hand-nut is tightened, substantially as set forth.

5. In combination with the saw, and its table having the downwardly-flanged edge in 120 square relation to the axis or plane of the saw, the guide or work-gage comprising a guide-head supported and adjustable upon the flanged edge of the table, the guide-tongue pivoted upon said head and having a lug or 125 angle projecting downward within said head, and the oppositely-directed lateral supporting-screws set in the sides of the head and engaging in depressions on the respective sides of said lug, for supporting and varying the alinement of the guide-tongue, substantially as set forth.

6. In a saw-guide adapted for support and adjustment on the flanged edge of the saw-

table, the combination of the guide-head having the flange-pocket therein, the friction bar or plate within said pocket, the flat bow-spring at the back of said friction-bar, and the check-screws threaded in the guide-head and impinging at the back of the bearing ends of said spring, for the purpose set forth.

7. In combination, as described, the table having the depending flange and the toothed rack along its edge, the guide, the guide-head underlocking said flange, the friction-bar within the head fitting the inclined face of the table-flange, the endwise-movable shaft carrying a pinion and washer at the back of said friction-bar, the intermediate gears mounted in the guide-head and meshing with said pinion and table-rack, the hand-wheel, its hub embracing and carrying said shaft, and the thumb-nut on the threaded outer end of said shaft, for the purposes set forth.

8. The combination with the saw-table having the parallel edges and depending edge flange; of a sawing-guide supported by a guiding-head that slides on the front flanged edge of said table, and a rear-end-clamping device having a gripping-piece with a lip that engages beneath the edge of the table, and a grip-operating means arranged upon the guide bar or tongue within convenient reach of the operator, for tightening and releasing said rear-end clamp, for the purposes set forth.

9. The combination with the saw-table having the straight flanged edges, and the guide-head adjustable thereon, of the guide-tongue having the rear-end opening and inclined surface adjacent thereto, the vertically-movable grip-piece having a lip that engages beneath the table edge, the endwise-movable bar having a wedge-shaped end that acts in conjunction with the inclined surface of the tongue for tightening or releasing said grip; and a pivoted cam and handle mounted upon the guide-tongue within convenient reach of the operator and adapted for moving said slide-bar, for locking and unlocking the grip devices, substantially as set forth.

10. In a saw-guide, the combination of a

guide tongue or bar, a supporting-head therefor adapted for embracing a flanged table edge, and standing below the base level of the guide-tongue, and a rear-end-grip device provided with means for operating the same, arranged between the lateral face edges of the guide-tongue, substantially as set forth. 55

11. In combination, with the machine-table having the plain ungrooved top surface and depending lip or flange along its edge, the guide or work-gage extending over the tabletop and supported by a guide-head on the outer edge of said table, the tongue of said guide provided with central bosses having vertical holes 9 therein; the detachable-high-fence plate 10 provided at its back with ear projections 24 having vertical pins 25 fixed therein that match and are insertible in holes in the guide-tongue, said high fence being adapted for support and use in reverse position at either side of the guide-tongue, substantially as set forth. 70

12. In combination, with the guide-tongue and guide-head; the detachable extension-bar made the same width as the guide-tongue, and forming a continuous straight edge therewith; means for connecting said bar with 75 said tongue; and the gage-stop supported thereon as described, and adapted for adjustment and use on either the extension-bar or guide-tongue, substantially as set forth.

13. The gage-stop b consisting of the detachable furcated clasp adapted for support astride the extension-bar and gage-tongue, and adjustable for use in upright or inclined positions; said gage-stop provided with projecting end lugs 30, lateral ledges 31, and lower 85 angular surfaces 33, and a set-screw or means for securing said stop in its adjusted position; in combination with the saw-guide tongue and the extension-bar, substantially as set forth. 90

Witness my hand this 28th day of September, 1897.
